CLAIM

The ornamental design for a circular dentifrice patch, as
shown and described.

DESCRIPTION

The present application file contains at least one drawing
executed in color. Copies of this patent or patent application
publication with color drawing(s) will be provided by the
Office upon request and payment of the necessary fee.

FIG. 1 is a perspective view of a circular dentifrice patch;

FIG. 2 is a front view thereof;

FIG. 3 is a left side view thereof;

FIG. 4 is a rear view thereof;

FIG. 5 is a right side view thereof;

FIG. 6 is a top plan view thereof;

FIG. 7 is a bottom plan view thereof;

FIG. 8 is a perspective view of a second embodiment of a
circular dentifrice patch;

FIG. 9 is a front view thereof;

FIG. 10 is a left side view thereof;

FIG. 11 is a rear view thereof;

FIG. 12 is a right side view thereof;

FIG. 13 is a top plan view thereof;

FIG. 14 is a bottom plan view thereof;

FIG. 15 is a perspective view of a third embodiment of a
circular dentifrice patch;

FIG. 16 is a front view thereof;

FIG. 17 is a left side view thereof;

FIG. 18 is a rear view thereof;

FIG. 19 is a right side view thereof;

FIG. 20 is a top plan view thereof;

FIG. 21 is a bottom plan view thereof;

FIG. 22 is a perspective view of a fourth embodiment of a
circular dentifrice patch;

FIG. 23 is a front view thereof;

FIG. 24 is a left side view thereof;

FIG. 25 is a rear view thereof;

FIG. 26 is a right side view thereof;

FIG. 27 is a top plan view thereof;

FIG. 28 is a bottom plan view thereof;

(Continued)

FIG. 29 is a perspective view of a fifth embodiment of a circular dentifrice patch;
 FIG. 30 is a front view thereof;
 FIG. 31 is a left side view thereof;
 FIG. 32 is a rear view thereof;
 FIG. 33 is a right side view thereof;
 FIG. 34 is a top plan view thereof; and,
 FIG. 35 is a bottom plan view thereof.
 The broken lines illustrate the environment of the circular dentifrice patch and form no part of the claimed design.
